INDICATING DEVICE FOR REGULATION OF
TIMEPIECES

Elza E. Wiford, Sidney, Ohio

Application November 28, 1947, Serial No. 788,444

3 Claims. (Cl. 73—6)

1

This invention relates to a device for indicating whether a timepiece is running fast, slow or on time.

An object of the invention is to provide a device of this kind in which a time-conformed unit is operated in association with a synchronizing unit conformable to the ticking of a timepiece to be regulated for determining by a cooperating indicator, what disparity exists between the timepiece and the time-conformed unit.

Another object is the provision of such a device in which the operation is simple and adapted to be performed in a minimum of time.

Another object is to provide a novel and effective synchronizing key for use with regulating devices of the nature indicated.

These and other objects are attained by the means described herein and illustrated in the accompanying drawings, in which:

Figure 1 is a rear elevational view, with parts broken away, of a regulating device of my invention.

Figure 2 is a cross-sectional view on line 2—2 of Figure 1.

Figure 3 is a top plan view of the actuator or key forming part of my invention.

Figure 4 is a side elevational view of the same.

Figure 5 is a front elevational view of the upper part of the regulating device.

Figure 6 is an enlarged fragmental view on line 6—6 of Figure 4.

Briefly, my invention comprises timing elements including means for revolving a contact at a constant, pre-determined rate of speed representing a time-standard, and synchronizing elements comprising a cam and indicator and means for rotating the revolving contact against the cam at intervals reflecting the ticking of a timepiece to be regulated. The relationship of cam and contact is such that when the timepiece is running on time there is no movement of the cam (and attached indicator) by the contact. But when the timepiece is slow or fast, said relationship is modified and the cam and indicator are moved in one direction, in the one instance, and the opposite direction, in the other instance, so that the person adjusting the timepiece can determine, by observing the indicator, what the adjustment must be and carry out the same until the indicator remains motionless.

In greater detail and with reference to the drawings: my invention comprises a main housing or case 10 comprising a base 11 and front and rear walls 12 and 13, mounted as by brackets 14 (Figure 2) on the base. Said walls may be

2

connected by rods 14'. A dial 15 may be positioned on the front wall 12. A subsidiary or smaller housing 16 is secured to the rear wall 13.

An electromagnet 17 is attached as at 18, interiorly of housing 10 and projects as at 19, into the smaller housing 16. A shaft 20 is rotatably mounted, as at 21 and 22, in the front wall of housing 10 and the rear end of housing 16. The forward end of shaft 20 projects through dial 15 and has secured thereto a hand or indicator 23, one end of which carries a weight 24 for normally holding the indicator in an upright position. Adjacent its rear end, shaft 20 has secured thereto a small cam 25.

15 A movable contact means for the cam 25 is provided in the following manner. A synchronized, alternating current motor 27 is positioned in the bottom of housing 10, together with suitable motor-starting means including a transverse shaft 28 (Figure 2) journaled in the front and rear walls of said housing and provided at the rear end with a knob 29 adapted to be turned with the fingers for starting the motor. Suitable wire connections 30 are provided for supplying current to the motor from an adjacent source.

20 The shaft 28, interiorly of housing 10, has a spur gear 31 secured thereto, which meshes with a large gear 32 secured, as at 33, to a journal shaft 34 rotatably surrounding the shaft 20. Shaft 34 is rotatively supported in front wall 12 and within electromagnet 17. Said journal shaft projects into smaller housing 16 and there has secured thereto an arm 35. One end of said arm carries a transverse bearing 36 through which a short axis rod 37 rotatably projects, the rod having fastened to or integral with its ends a pair of projecting members, one constituting a cam contact 38 and the other, an electromagnetic arm 39. Said contact and arm are limited in their rotational movement by suitable stop means within the bearing 36 and are normally urged, by a small spring 40, attached to said arm and axis rod 37, in a direction outwardly of arm 35, that is, to the left and upwardly, as seen in Figure 1. A counter-weight 35' is carried by arm 35 at the end opposite the bearing 36.

25 The contact 38 is designed to cooperate with cam 25 and arm 39 with the electromagnet 17. As will be seen in Figures 1 and 2, a contact plate 41 is secured to journal shaft 34 adjacent the arm 35, being separated therefrom by a spacer 42 and from the electromagnet by a spacer 43.

30 Associated with the structure thus far described is an actuator or key unit 44 seen at the left hand side of Figure 1 and in Figures 3 and 4.

This unit comprises a base 45 having a pair of point contacts 46 and 46' mounted thereon in opposed relation. Member 47 is a mere abutment while member 48 is an electrical contact, as will be further explained. Forwardly of these, on a standard 47, an operating lever 48 is pivotally mounted, being preferably made up of a key 49, and a contact section 50, rigidly but adjustably connected together as at 51. The outer end of key 49 is provided with an insulating covering 51.

Adjacent the end of base 45, opposite key 49, a standard 52 has positioned thereon, and fixed together for common rotation to the right (Figure 6) a switch plate 53 and a ratchet 54, spaced from plate 53 by a spacer 55. Plate 53, except for a contact segment 56 set therein, is of non-electrical-conducting material, while ratchet 54, spacer 55 and lever 48 are all electrical conductors.

A pawl 58 is mounted pivotally as at 59 on the end of section 50 of lever 48 and is urged into engagement with ratchet 54 by virtue of a spring 60 on said section 50 and bearing against an ear 61 formed on the pawl.

On the base 45, adjacent the ratchet unit above described, an electrical connection stud 62 is positioned. It supports a contact finger 63 bearing resiliently against the periphery of switch plate 53 and intermittently contacting the segment 56 of said plate, upon rotation of the latter, as will be elaborated upon.

An electric circuit, herein shown as a battery circuit, embraces the actuator unit above described and the electromagnet 17. This circuit is clearly indicated in Figure 3. The point contact 46 on key base 45 is shown as connected through line A with a terminal 64, which, through a line B proceeds to a battery C. From thence, a line D proceeds to a terminal 65 on base 45 which is connected by line E with one side of the electromagnet 17, shown diagrammatically in Figure 3. The other side of the electromagnet is connected by line F with the connection stud 62 on key base 45.

It should now be explained that the gearing 31-32 driven by motor 27 is such as to rotate the journal shaft 34, and the arm 35 thereto secured, at a synchronized and pre-determined rate, representing exact units of time. Shaft 20 is not rotated by said gearing. As illustration, arm 35 may be made to rotate so as to carry the cam contact 38 around a complete turn every three seconds. Cooperatively, the ratchet 54 may be formed with a certain number of teeth (fifteen as shown) each representing a tick of a standard watch or timepiece wherein five ticks per second are produced, the total number of teeth representing three seconds.

Operation is as follows: the watchmaker, clock-maker, jeweler, or other person utilizing this regulating device, starts motor 27 by plugging in its connections 30 and actuating the actuator knob 29. Then such person, closely noting the ticking of the timepiece to be regulated, actuates key 49 of the synchronizing unit between the point contacts 46 and 47 in synchronism with such ticking. Actuation of the lever 48 by key 49 rotates the ratchet 54 tooth-by-tooth, in synchronism with the ticking of the timepiece. When such rotation brings contact segment 56 of switch plate 53 into contact with finger 63, the battery circuit is completed through the key unit and the electromagnet. The latter magnetically attracts the arm 39, whereby the cam contact 38 is simultaneously rotated toward cam 25. The high and

low peripheral sectors of the cam are so related to the cam contact 38 that the latter, upon such inward movement, passes across the low peripheral cam sectors when the key actuation is synchronous with the rotation of arm 35, which carries the cam contact. As a consequence, there is no resultant actuation of the cam and of the shaft 20 and indicator 23 connected therewith. But a disparity between the actuation rate of the key (that is, the ticking of the timepiece) and the rotation of arm 35, results in rotation of cam contact 38 on an off-beat, so to speak, when the finger 63 meets the contact segment 56 and actuates the electromagnet. As a result, the cam contact strikes against the high peripheral part of the cam and swings the cam, and consequently the indicator 23 (which the workman, of course, keeps under constant observation), to show that the timepiece is running either fast or slow. To indicate whether fast or slow, the cam contact may be arranged to strike opposite sides of the apex portion of the cam, resulting in swinging of the indicator to the left of the dial, if the timepiece is running slow, and to the right if it is running fast. The timepiece is then adjusted and again tested, as explained, and when the indicator remains motionless, the timepiece is known to be running on time. Shaft 20, carrying cam 25 and pointer 23, is normally biased to the position shown in Figures 1 and 2 by the weight 24.

It may be further explained, as to use of the device, that the initial actuation of the cam contact is discounted, in the testing operation, since the contact segment 56 is any undetermined number of steps (or ratchet teeth) away from the contact finger 63. Upon the initial contact of said finger and contact segment, however, the device is conditioned for accurate testing. Such contact (and the resultant actuation of the cam contact 38) will occur every three seconds. In the meantime, arm 35 is rotating around the cam 25, every three seconds (in the illustration given) and a full revolution of arm 35 brings the contact 38 to a position wherein said contact, if then actuated, will not meet the higher or more off-center parts of the cam and hence the indicator 23 will not be moved. But if the tick of the time-piece does not coincide with these predetermined revolutions of arm 35, then the cam contact will be actuated against high parts of the cam and the indicator will register "fast" or "slow," accordingly.

What is claimed is:

1. An indicator device for use in regulating timepieces comprising a hollow main housing including front and rear walls, a subsidiary housing arranged exteriorly of and secured to the rear wall of said main housing and in communication with the latter housing, an electromagnet positioned within said main housing and supported in the rear wall of the latter housing and extending into the subsidiary housing, a shaft positioned within said main and subsidiary housings and rotatably journaled on the front wall of said main housing and the rear end of said subsidiary housing and having one end projecting from said front wall, an indicator positioned exteriorly of said front wall of said main housing and secured to said one end of said shaft, a cam positioned within said subsidiary housing and fixedly secured to said shaft, an arm disposed transversely of said shaft and rotatably mounted intermediate its ends within said subsidiary housing coaxial with and independent of said shaft, a first contact member positioned contiguous to said electromagnet and said arm and mounted on one end of said arm for

rotary movement toward said electromagnet upon energization thereof, a second contact member connected to said first contact member and mounted on said one end of said arm for movement toward and into engagement with said cam in response to the rotary movement of said first contact member, motive means operatively connected to said arm for rotating the latter at a predetermined rate, and manually actuated means electrically connected to said electromagnet for energizing the latter at intervals synchronous with the ticking of the timepiece to be regulated, said cam and said second contact member being disposed relative to one another.

2. An indicator device according to claim 1 including in addition a counterweight positioned contiguous to the other end of said arm and secured thereto for urging the latter into a normally upright position.

3. An indicator device according to claim 1 including in addition a counterweight positioned contiguous to the other end of said arm and secured thereto for urging the latter into a normally upright position, and resilient means operatively connected to said contact members for normally biasing said contact members in to a select position with respect to said arm.
